CLAIM

I claim the ornamental design for a low cabinet, as shown and described.

DESCRIPTION

FIG. 1 is a front perspective view of a low cabinet of Applicant's design;

FIG. 2 is a front elevational view thereof;

FIG. 3 is a rear elevational view thereof;

FIG. 4 is a top plan view thereof;

FIG. 5 is a bottom plan view thereof;

FIG. 6 is a first side elevational view thereof, the second side elevational view opposite the first side elevational view and being a mirror image thereof; and,

FIG. 7 is a sectional view thereof, taken along line 7-7 in FIG. 2.

Where included, broken lines showing environment or structure are for illustrative purposes only and form no part of the claimed design.
